FLASHLIGHT SWITCH

Wesley J. Officer, Hampden, and Orville T. Wood,
Clinton, Mass., assignors to Blake Manufacturing Corporation, Clinton, Mass., a corporation of Massachusetts

Application June 6, 1936, Serial No. 83,880

14 Claims. (Cl. 200—60)

Our invention relates to improvements in flashlight switches, and particularly to that type of flashlight switch commonly known in the art as a three position, locking, slide switch. The three positions inferred are an open circuit position, an intermittent or flash position, in which the circuit is closed by intermittent pressure on some part of the switch, and a closed circuit position or steady light position.

10 This invention is an improvement on the switch construction disclosed in our copending application filed January 29th, 1935, Serial Number 3,934.

An object of this invention is to provide, in a switch construction including a helical spring, 15 means co-operating with the helical spring for positioning a movable member relative to electrical contacts associated with the switch construction.

A second object of this invention is to provide, 20 in a slide switch, a slide construction comprising one or more members movable relative to the switch housing and co-operating with a helical spring, and means on one of said members for positioning and holding the spring.

25 A third object of this invention is to provide, in a slide switch embodying a two part slide construction, co-operating interlocking means for preventing relative side motion of the slide members, so that the same slide construction may be 30 used, either in a single switch housing, or in a double switch housing, similar to that illustrated in the "Duo-lite" flashlight disclosed in the patent to Officer and Seaver #1,969,320, issued August 7, 1934.

35 Other objects and advantages of this invention will be more completely disclosed and described in the accompanying drawings, the specification, and the appended claims.

Broadly, our invention comprises, in combination with a supporting member and a switch lead, 40 a housing, a slide construction within the housing comprising a top member and a bottom member independently movable, relative to each other, vertically but relatively immovable longitudinally, 45 and transversely, a helical spring between the top and bottom members for normally spacing the members, an operating button secured on one of the members, electrical contact means on the switch lead and exposed within the housing, 50 open circuit, flash, and closed circuit positions in the housing, operative connecting means between the spring and one of the members, and means on the spring co-operating with the positions in the housing for positioning the slide construction, relative to the electrical contacts.

A preferred embodiment of our invention is illustrated in the accompanying drawings, in which:

Fig. 1 is a longitudinal sectional view of a switch construction, assembled on a flashlight 5 casing, with the slide construction in open circuit and locked position.

Fig. 2 is a view similar to Fig. 1, showing the slide construction in intermittent or flash position.

Fig. 3 is a view similar to Fig. 1, showing the slide construction in closed circuit position.

Fig. 4 is a horizontal sectional view, taken on the line 4—4 of Fig. 1.

Fig. 5 is a transverse sectional view, taken on the line 5—5 of Fig. 1.

Fig. 6 is a perspective view of the bottom slide member.

Fig. 7 is a cross sectional view, taken on the line 7—7 of Fig. 6.

Fig. 8 is a perspective view of the top slide member.

Fig. 9 is a transverse sectional view of a double switch housing, incorporating the switch slide construction and a second slide construction for 25 a diffusing sleeve member.

Fig. 10 is a longitudinal sectional view, taken on the line 10—10 of Fig. 9.

Fig. 11 is a horizontal sectional view, taken on the line 11—11 of Fig. 9.

Fig. 12 is a plan view of the portion of the casing enclosed within the double housing.

Fig. 13 is a perspective view of the bottom member used for the diffusing sleeve slide.

Fig. 14 is a longitudinal sectional view, illustrating a modified form of flashlight switch.

Fig. 14a is a sectional view on the line 14a—14a of Fig. 14.

Fig. 15 is a plan view of the coiled spring, shown in Fig. 14.

Fig. 16 is a view similar to Fig. 14, illustrating a further modification.

Fig. 17 is a plan view of the coiled spring, shown in Fig. 16.

Fig. 18 is a view similar to Fig. 14, illustrating 45 another modification, and

Fig. 19 is a plan view of the coiled spring, shown in Fig. 18.

Referring now to the drawings in detail, in which like numerals refer to like parts throughout:

The flashlight construction, shown in Figs. 1—8, inclusive, will be first described.

A metallic switch lead 1 is secured on a strip 2 of fiber, or other suitable insulating material by 55

means of rivets or eyelets 3 and 4, which also serve as contact members for closing the electrical circuit. The strip 2 is secured on the inner surface of a casing 5 by means of rivets or eyelets 6, and a housing 7 is secured on the outer surface of the casing 5 by means of rivets or eyelets 8 (see Fig. 5). Openings 9 in the casing 5 and an opening 10 in the switch lead 1 provide clearance for preventing a short in the electrical circuit.

10 A slide construction including a top member 11, bottom member 12, and helical, expansible spring 13, is confined within the housing 7, and may be moved longitudinally within the housing 7 by manipulation of a button 14 which projects upwardly through an opening 15 in the housing 7 and which is secured to the top member 11 by engagement of tabs 16 formed on the button 14 in slots 17, formed in the member 11. Transverse movement of the member 11 within the housing 7 is prevented by engagement of the button 14 against the sides of the opening 15. Transverse movement of the bottom member 12, relative to the top member 11, is prevented by engagement of the member 12 against a side wall 7' of the housing 7 and by engagement of lugs 18 formed on the member 12 with end walls 19 of the member 11. As shown in Figs. 4 and 8, the end walls 19 are cut away at 20 to provide for the lugs 18 and to permit vertical movement of the member 12, relative to the member 11. Longitudinal movement of the member 12, relative to the member 11, is prevented by engagement of oppositely extending portions 21 and 22 on the member 12 with the end walls 19 on the member 11. The end walls 19, of the member 35 11, are bent inwardly to form inwardly extending flange portions 23 and 24, and the portions 21 and 22 of the member 12 are movable freely in a vertical direction between the portions 23 and 24, respectively, and the main body, or top portion of 40 the member 11.

The bottom member 12 is formed with a base portion 25 having the opposite edges 26 and 27 thereof bent upwardly, as indicated in Figs. 6 and 7, to assist in retaining the helical, expansible 45 spring 13, which is inserted between the members 11 and 12 and normally exerts a force to normally space these members apart, the limit of this movement being the space between the casing 5 and top 7" of the housing 7. An end 28, of the spring 50 13, is engaged in a notch 29 formed in a downwardly extending side flange 30 on the top member 11, and the opposite end 31 of the spring 13 is formed with a hooked, or bent portion 32, for engagement in station grooves 33, 34, and 35, 55 formed in the side 7' of the housing 7.

The normal, or open circuit position, of the slide is shown in Fig. 1. In this position, the slide is securely locked against accidental movement by engagement of a downwardly extending lug 36 60 formed in the housing 7 in a slot 37 formed in the member 11. Also, the portion 32 of the spring 13 is engaged in the groove 33, as indicated in Figs. 1 and 4. It will be noted, that in this position, no portion of the slide may be brought into engagement with either of the contacts 3 or 4. If the flange 24 is pushed downwardly, it will not contact the rivet 3. To move the slide from this open circuit position, the button 14 is pushed downwardly, thus clearing the member 11 from the 65 locking lug 36, then, forwardly, until the portion 32 of the spring 13 snaps into either of the grooves 34 or 35, as desired. In the intermittent, or flash position, indicated in Fig. 2, the portion 32 of the spring 13 is engaged in the intermediate 70 75 station groove 34, and downward pressure on the

button 14 will engage the flange 24 on the contact rivet 3. In the closed circuit position, indicated in Fig. 3, the portion 32 of the spring 13 is engaged in the groove 35, and the base portion 25 of the bottom member is located on the contact rivet 4. In this position of the slide, pressure on the button 14 may be removed without disturbing the electric circuit. 5

In flashlights embodying this type of switch, it is customary to include either the casing 5, or 10 housing 7, in the electric circuit, as a ground.

An adaptation of the switch construction, described above, to a flashlight having a diffusing sleeve, (not shown), actuated by an operating strip, or member, slidably supported on the inside 15 of the flashlight casing, is illustrated in Figs. 9-13, inclusive. A switch construction identical with that shown in Figs. 1-8, inclusive, is enclosed within a double housing 38, one-half 39 of which is similar to the housing 7, and the other half 40 20 adapted to receive a slide construction, as clearly illustrated in Figs. 10 and 11. In the construction, shown in Fig. 10, an operating strip or member 41, for a diffusing sleeve (not shown) is slidably secured on the inside of the casing 5 by means of 25 eyelets, or rivets 42, which extend outwardly through slots 43, formed in the casing 5, and are secured on a bottom slide member 44. The bottom member 44 is engaged, in the same manner as the member 12, in a top member 45, on which is secured an operating button 46. The bottom member 44 (see Fig. 13) is provided with raised side flanges 47 for retaining a helical spring 48. The top member 45 is formed with a ridge, or projection 49, which may be engaged either in a slot 50, 35 formed in the portion 40 of the housing 38 for the button 46, or in a groove 51, formed in the portion 40, as indicated in Fig. 10; co-operation of the groove 51 and slot 50 with the ridge 49 marking the limits of movement of the member 41. An 40 end 52 of the spring 48 may be retained in a slot 53, formed in a side flange 54 of the top member 45, in a similar manner to the switch construction. 45

In Fig. 11, an alternative arrangement of stations for the diffusing sleeve slide is illustrated. 45 In this construction, the two station position grooves 55 and 56 are formed in the side of the housing 38, similarly to the grooves 33, 34, and 35 for the switch, and the spring 48 is provided with a hooked or bent end 57 which co-50 operates with the grooves 55 and 56.

A modification of the slide construction, incorporating a coiled, or helical spring, is illustrated in Figs. 14-19, inclusive. In this construction, a coiled spring is used and so placed as to position its axis approximately perpendicular to the sides of the housing, instead of to the top of the housing, as previously disclosed. The effect of this construction is to eliminate the bottom member of the slide and utilize the torsional 55 force of the spring in the operation of the slide. In the construction, illustrated in Fig. 14 and Fig. 15, a housing 60 is secured on a casing 61, in any suitable manner, and a bottom plate 62 is secured within the housing in such a manner, 65 as to provide a space 63, between the casing 61 and plate 62. An insulated switch lead 64 is secured on the under side of the plate 62 and has portions thereof stripped of insulation and bent upwardly at 65 and 66 to project through 70 openings 67 in the plate 62 and serve as electrical contacts. The switch lead 64 enters the casing 61, through an opening 68, formed in the casing 61. An advantage of this construction is the ability to assemble the switch construction, in- 75

cluding the switch lead, completely, before installation on the casing. A top slide member 69, provided in the usual manner with an operating button 46, is normally held in spaced relation to the plate 62 and against the top of the housing 60 by a coiled spring member 70, which is held in position, relative to the member 69 by engagement of an end 71 thereof in an opening 72, formed in the member 69. The opposite end 73 of the spring 70 is formed with a hook, or bent portion 74, which snaps into place in the position grooves 75, 76, and 77, formed in the fixed plate 62, as the slide is moved from one position to another. The electrical contacts are made in a similar manner to that described for Figs. 1, 2, and 3, the flange 78 on the member 69 being engaged intermittently, by pressure on the button 46, on the contact 66, and the spring 70 being engaged on the contact 65 for continuous contact. Side flanges 79, on the member 69, serve as retainers for the spring 70. Fig. 14a shows the relative lateral position of lead 64 and position grooves 75, 76, and 77.

In the construction, shown in Figs. 16 and 17, a spring 80, similar to the spring 70, is used. The spring 80 is retained between side flanges 81 on a top slide member 82, and the flanges 81 are bent inwardly and notched at 83 to engage the spring 80, an end 84 of the spring 80 is extended 30 and bears on the outer surface of the battery-receiving casing 5, and the opposite end 85 of the spring 80 is also extended and formed with a hooked, or bent portion 86, which projects through an opening 87 in the member 82, to engage in the position grooves 88 formed in the fixed housing 89. The electric circuit is closed, either by engagement of a flange 90 on the member 82, on the contact 3, or by engagement of the spring 80 on the contact 4.

The construction illustrated in Figs. 18 and 19 is similar to that shown in Figs. 16 and 17, except an end 92 of the spring 91 is retained in an opening 72 in the member 69, as in Fig. 14, and the opposite end 93 of the spring 91 is provided 45 with a hooked, or bent portion 94 which may be engaged in the position grooves 95, formed in the housing 96.

What we claim is:—

1. In a circuit closer for flashlights and electric hand lanterns, in combination, a relatively fixed part comprising a battery containing casing portion and housing means relatively fixed with respect to the casing portion and formed with an opening and enclosing a switch contact, 50 said relatively fixed part being formed with a plurality of recesses disposed in predetermined spaced relation, and a movable member part relatively loosely received in the housing means and adapted to be reciprocated therein, manually engageable means carried with the movable member part and disposed in the opening of the housing means to effect movement of said movable member part, and a coil spring carried with the movable member part whereof at least one 55 free end extends away from the coils, said movable member part being formed with a cut-away portion receiving a portion of the coil spring and thereby positioning the coil spring with respect thereto, said free end being selectively engaged with the recesses, respectively.

2. In a circuit closer for flashlights and electric hand lanterns, in combination, a relatively fixed part comprising a battery containing casing portion and housing means relatively fixed with respect to the casing portion and formed

with an opening and enclosing a switch contact, 5 said relatively fixed part being formed with a plurality of recesses disposed in predetermined spaced relation, and a movable member part relatively loosely received in the housing means and adapted to be reciprocated therein, manually engageable means carried with the movable member part and disposed in the opening of the housing means to effect movement of said movable member part, a coil spring carried with the movable member part whereof at least one free end extends away from the coils, said movable member part being formed with a cut-away portion receiving a portion of the coil spring and thereby positioning the coil spring with respect thereto, 10 said free end being selectively engaged with the recesses, respectively, and means carried with the movable member part to make electrical connection with the switch contact.

3. In a circuit closer for flashlights and electric hand lanterns, in combination, a relatively fixed part comprising a battery containing casing portion and housing means relatively fixed with respect to the casing portion and formed with an opening and enclosing spaced switch contacts, 15 said relatively fixed part being formed with a plurality of recesses disposed in predetermined spaced relation, and a movable member part relatively loosely received in the housing means and adapted to be reciprocated therein, manually engageable means carried with the movable member part and disposed in the opening of the housing means to effect movement of said movable member part, a coil spring carried with the movable member part whereof at least one free end 20 extends away from the coils, said movable member part being formed with a cut-away portion receiving a portion of the coil spring and thereby positioning the coil spring with respect thereto, said free end being selectively engaged with the recesses, respectively, and means carried with the movable member part to make electrical connection with the switch contacts selectively.

4. In a circuit closer for flashlights and electric hand lanterns, in combination, a relatively fixed part comprising a battery containing casing portion and housing means relatively fixed with respect to the casing portion and formed with an opening and enclosing a switch contact, 25 said relatively fixed part being formed with a plurality of recesses disposed in predetermined spaced relation, and a movable member part relatively loosely received in the housing means and adapted to be reciprocated therein, manually engageable means carried with the movable member part and disposed in the opening of the housing means to effect movement of said movable member part, a coil spring carried with the movable member part whereof at least one free end 30 extends away from the coils, said movable member part being formed with a cut-away portion receiving a portion of the coil spring and thereby positioning the coil spring with respect thereto, said free end being selectively engaged with the recesses, respectively, and means carried with the movable member part to make electrical connection with the switch contacts selectively.

5. In a circuit closer for flashlights and electric hand lanterns, in combination, a relatively fixed part comprising a battery containing casing portion and a housing relatively fixed with respect to the casing portion and formed with an opening and enclosing a switch contact, 35 said relatively fixed part being formed with a plurality of recesses disposed in predetermined spaced relation, a composite member part relatively loosely received in the housing and slidably on the casing portion, said composite member comprising a 40

- first member, a second member, interengaging means for the first and second member limiting separating movement of said members, a coil spring normally urging said first and second members away from one another and manually engageable means carried with said composite member and disposed in the opening of the housing to effect movement of said first and second members in vertical and horizontal planes to selectively make contact with the switch contact, said movable member part being formed with a cut-away portion securing a free end of the coil spring, the other free end being selectively engaged with the recesses, respectively.
13. 6. In a circuit closer for flashlights and electric hand lanterns, in combination, a relatively fixed part comprising a battery containing casing portion and a housing relatively fixed with respect to the casing portion and formed with an opening and enclosing spaced switch contacts, said relatively fixed part being formed with a plurality of recesses disposed in predetermined spaced relation, a composite member part relatively loosely received in the housing and slid-able on the casing portion, said composite member comprising a first member, a second member, interengaging means for the first and second member limiting separating movement of said members, a coil spring normally urging said first and second members away from one another and manually engageable means carried with said composite member and disposed in the opening of the housing to effect movement of said first and second members in vertical and horizontal planes to selectively make contact with the switch contacts, said movable member part being formed with a cut-away portion securing a free end of the coil spring, the other free end being selectively engaged with the recesses, respectively.
14. 7. A manually actuatable member for controlling the light emitted from flashlights and electric hand lanterns, in combination, a relatively fixed part comprising a battery containing casing portion and housing means relatively fixed with respect to the casing portion and formed with an opening, a composite member part relatively loosely received in the housing and slidable on the casing portion, said composite member comprising a first member having downwardly directed ends each of which is formed with an inwardly directed flange, a second member having upwardly directed ends each of which is formed with an outwardly directed flange in cooperative engagement with the first named flanges to limit separating movement of said members, a coil spring normally urging said first and second members away from one another, said relatively fixed part being formed with a plurality of recesses disposed in predetermined spaced relation, said movable member part being formed with means engaging the spring, a free end of said spring being selectively engaged with said recesses, respectively.
15. 8. A manually actuatable member for controlling the light emitted from flashlights and electric hand lanterns, in combination, a relatively fixed part comprising a battery containing casing portion and housing means relatively fixed with respect to the casing portion and formed with an opening, a composite member part relatively loosely received in the housing and slidable on the casing portion, said composite member comprising a first member having downwardly directed ends each of which is formed with an inwardly directed flange, a second member having upwardly directed ends each of which is formed with an outwardly directed flange in cooperative engagement with the first named flanges to limit relative movement of said members, a coil spring normally urging said first and second members away from one another, said relatively fixed part being formed with a plurality of recesses disposed in predetermined spaced relation, said movable member part being formed with a plurality of recesses disposed in predetermined spaced relation, said movable member part being formed with a recess engaging the spring, a free end of said spring being selectively engaged with said first named recesses, respectively.
16. 9. A manually actuatable member for controlling the light emitted from flashlights and electric hand lanterns, in combination, a relatively fixed part comprising a battery containing casing portion and housing means relatively fixed with respect to the casing portion and formed with an opening, a composite member part relatively loosely received in the housing and slidable on the casing portion, said composite member comprising a first member having downwardly directed ends each of which is formed with an inwardly directed flange, a second member having upwardly directed ends each of which is formed with an outwardly directed flange to limit relative movement of said members, a coil spring normally urging said first and second members away from one another, said relatively fixed part being formed with a plurality of recesses disposed in predetermined spaced relation, said movable member part being formed with flanges to confine the spring, a free end of said spring being selectively engaged with said recesses, respectively.
17. 10. A manually actuatable member for controlling the light emitted from flashlights and electric hand lanterns, in combination, a relatively fixed part comprising a battery containing casing portion and housing means relatively fixed with respect to the casing portion and formed with an opening, a composite member part relatively loosely received in the housing and slidable on the casing portion, said composite member comprising a first member having downwardly directed ends each of which is formed with an inwardly directed flange, a lug on each flange, a second member having upwardly directed ends each of which is formed with an outwardly directed flange in cooperative engagement with the lug on the first named flanges to limit relative movement of said members, a coil spring normally urging said first and second members away from one another, said relatively fixed part being formed with a plurality of recesses disposed in predetermined spaced relation, said movable member part being formed with a recess engaging the spring, a free end of said spring being selectively engaged with said first named recesses, respectively.
18. 11. A manually actuatable member for controlling the light emitted from flashlights and electric hand lanterns, in combination, a relatively fixed part comprising a battery containing casing portion and housing means relatively fixed with respect to the casing portion and formed with an opening, a composite member part relatively loosely received in the housing and slidable on the casing portion, said composite member comprising a first member having downwardly directed ends each of which is formed with an inwardly directed flange, a lug on each flange, a second member having upwardly directed ends each of which is formed with an outwardly directed flange in cooperative engagement with the lug on the first named flanges to limit relative movement of said members, a coil spring normally urging said first and second members away from one another, said relatively fixed part being formed with a plurality of recesses disposed in predetermined spaced relation, said movable member part being formed with flanges to confine the spring, a free end of said spring being selectively engaged with said recesses, respectively.

urging said first and second members away from one another, said relatively fixed part being formed with a plurality of recesses disposed in predetermined spaced relation.

5 12. A manually actuatable member for controlling the light emitted from flashlights and electric hand lanterns, in combination, a relatively fixed part comprising a battery containing casing portion and housing means relatively fixed with respect to the casing portion and formed with an opening and a recess, said relatively fixed part being formed with a plurality of recesses disposed in predetermined spaced relation, and a movable member part relatively loosely received in the 10 housing means and adapted to be reciprocated therein and formed with projecting means disposed in the opening in one position thereof and in the recess in another position thereof, manually engageable means carried with the movable 15 member part and disposed in the opening of the housing means to effect movement of said member part, a coil spring carried with the movable member part whereof at least one free end extends away from the coils, said movable member 20 part being formed with a cut-away portion receiving a portion of the coil spring and thereby positioning the coil spring with respect thereto, said free end being selectively engaged with the recesses, respectively.

25 13. In a circuit closer for flashlights and electric hand lanterns, in combination, a relatively fixed part comprising a battery containing casing portion and housing means relatively fixed with respect to the casing portion and formed with an opening and enclosing a switch contact, said relatively fixed part being formed with a plurality of recesses disposed in predetermined spaced 30 relation, and a movable member part relatively

loosely received in the housing means and adapted to be reciprocated therein, manually engageable means carried with the movable member part and disposed in the opening of the housing means to effect movement of said movable member part, and a coil spring carried with the movable member part whereof the free ends extend away from the coils, said movable member part being formed with a cut-away portion receiving a portion of the coil spring and thereby positioning the coil spring with respect thereto, a free end being selectively engaged with the recesses, respectively, the other free end being adapted to engage the contact. 10

15 14. In a circuit closer for flashlights and electric hand lanterns, in combination, a relatively fixed part comprising a battery containing casing portion and housing means relatively fixed with respect to the casing portion and formed with an opening and enclosing a switch contact, a member in the housing means having recesses disposed in predetermined spaced relation, and a movable member part relatively loosely received in the housing means and adapted to be reciprocated therein, manually engageable means carried with the movable member part and disposed in the opening of the housing means to effect movement of said movable member part, and a coil spring carried with the movable member part whereof at least one free end extends away from the coils, said movable member part being formed with a cut-away portion receiving a portion of the coil spring and thereby positioning the coil spring with respect thereto, said free end being selectively engaged with the recesses, respectively. 20 25 30 35

WESLEY J. OFFICER.
